COMPARTMENTED BOX LINER

James Raymond Loney, Cote St. Luc, Quebec, Canada,
assignor to Plastic Packaging Products Limited, Mon-
treal, Quebec, Canada

Filed Nov. 27, 1964, Ser. No. 82,845

Term of patent 14 years

(Cl. D58—13)

FIGURE 1 is a top plan view of a compartmented box liner, showing my new design;

FIGURE 2 is an end elevation; and

FIGURE 3 is a side elevation thereof.

I claim:

The ornamental design for a compartmented box liner, as shown.
